Margaret Michelson, New York, N. Y.

Application June 23, 1937, Serial No. 70,017

Term of patent 3½ years

To all whom it may concern:

Be it known that I, Margaret Michelson, a citizen of the United States of America, residing in Manhattan, county of New York, and State of New York, have invented a new, original, and ornamental Design for a Dress Ensemble, of which the following is a specification, reference being had to the accompanying drawing, forming part thereof, wherein,

Figure 1 is a front view of a dress ensemble showing my new design.

Figure 2 is a front view of the dress unit of the dress ensemble shown in Figure 1.

Figure 3 is a rear view of the dress unit of the dress ensemble.

Figure 4 is a front view of the jacket unit of the dress ensemble shown in Figure 1.

The rear portion of the jacket unit is conventional.

The contrastingly colored edgings on the sleeve portions of the jacket unit, and collar portion of the dress unit of the dress ensemble, represent leather pipings on the evening gown, as shown.

I claim:

The ornamental design for a dress ensemble, substantially as shown, and described.

MARGARET MICHELSON.
